CENTRIFUGAL PUMP.

1,278,721.

Specification of Letters Patent. Patented Sept. 10, 1918.

Application filed July 14, 1916. Serial No. 109,295.

To all whom it may concern:

Be it known that I, HENRI ARNOLD JOHANNES DE BIJLL NACHENIUS, mechanical engineer, residing at Haarlem, the Netherlands, have invented certain new and useful Improvements in Centrifugal Pumps, of which the following is a specification.

This invention relates to the centrifugal pumps, more particularly to pumps such as employed for pumping liquids mixed with gravel, sand, mud or the like.

As is well known in the use of so called gravel pumps as also of centrifugal pumps employed for emptying hoppers and the like, great trouble is encountered owing to wear, for which reason such pumps are provided with an exchangeable lining.

In order to allow for the impeller being brought into position, this lining, usually made in the shape of a centrifugal pump casing, is either split perpendicularly to its axis or across a straight, broken or curved line through its axis or is provided with an opening in the side wall, in practice closed by means of a cover. In spite of the hardness of the material of which such linings of gravel pumps are constructed, the grinding effect on the inner surface of the lining is so severe that the lining must be replaced after a short period of use.

Practice has proved that this grinding effect is especially severe along the joints between the parts of which the lining is composed and that this grinding effect is about proportional to the square of the velocity of the liquid.

In the pumps above referred to, in which the impeller is brought into the lining through an opening in the side wall, the joint between the cover and the wall forms a circle of a somewhat larger diameter than the diameter of the impeller, where the velocity of the liquid to be pumped is considerable, some 60 feet per second.

In all other well known constructions mentioned above the joints must necessarily pass a zone in which the velocity of the liquid is such that the grinding effect is destructive on the lining.

The object of the present invention is the construction of a pump in which these drawbacks are avoided. For this purpose the casing has joints only at or near the zone where the velocity of the liquid to be pumped attains a minimum.

This zone will be at or near the delivery opening, because the velocity decreases considerably from the periphery of the bucket wheel to the circumference of the casing. The opening by way of which the impeller may be brought into position is accordingly so disposed that all the joints are arranged at the circumference adjacent to the delivery opening in the casing; in fact the delivery opening itself may be arranged in the cover of the opening by way of which the impeller can be introduced into the casing. The delivery pipe connected to said opening may be constructed so as to gradually increase in section to the size of this opening.

The velocity of the liquid in the delivery opening is only 10 to 13 feet per second, so that the grinding effect in the neighborhood of this opening is very little indeed. Moreover, the joints of the cover are so arranged in relation to the direction of the flow that along the same the casing or lining is practically not subjected to wear.

The invention is illustrated in the accompanying drawings.

Figure 1 is a side view of a pump constructed according to the invention; Fig. 2 is a vertical section across a plane through the axis; Fig. 3 shows a pump of modified construction.

Referring to Figs. 1 and 2, the casing 3 is shown as being of the form generally used in connection with gravel pumps. The impeller 4 has a diameter indicated by the dimension line 6, which is shorter than the length of the opening in the circumference of the casing, as indicated by the line 7, such opening being closed by means of the cover 8 which also serves as a delivery connection. The opening is also wider than the impeller 4 so that the impeller can be introduced into and removed from the casing through this opening. The inner part of the impeller communicates with the suction pipe 11 through a fixed pipe 9 provided with a packing device constituted by an adjustable slide ring 10.

The shaft is fixed into the impeller by means of a conical screw thread and the check plate 13. The impeller may of course be otherwise fixed to the shaft in any other suitable manner, it being important only that it shall be capable of passing through the opening covered by the casting 8.

The annular casing of a gravel pump

being much wider than the casing of an ordinary centrifugal pump, the velocity of the liquid will be small at or near the point 14. At the point 15 the liquid with low velocity mixes partly with the slow flow in the delivery pipe 16 so that at this point the velocity is inconsiderable, resulting in but very little wear along the joint.

Owing to the fact that as a result of the 10 simple form of casing required for gravel pumps correct distribution of the velocity of the liquid cannot be obtained, the pump according to Fig. 3 is also suitable from a constructional point of view. In the case of 15 the pump shown in Fig. 3 the circumference of the casing merges evenly into the delivery pipe 17 so that the impeller is, so to say, introduced into the casing in a tangential or radial direction through the delivery opening in the casing.

The pumps illustrated in the drawings are unlined. In each instance the casing is cast to the required dimensions and the connecting parts of the suction pipe and the 25 parts belonging to the packing device are so constructed that they may be adjusted relatively to one another. The casing therefore requires no machining. Replacement of the casing is less costly and occupies less time 30 than renewal of a lining of the usual shape.

Having now described my invention, what I claim as new and desire to secure by Letters Patent is:

1. In a centrifugal pump, an impeller, a 35 casing having an opening at its periphery large enough to permit the insertion of said

impeller, and a cover for said opening, the line of the joint between said cover and casing being entirely outside of the periphery of the impeller.

40

2. In a centrifugal pump, an impeller, a casing having an opening at its periphery large enough to permit the insertion of said impeller, and a cover for said opening, the line of joint at the inner wall of said casing 45 between said cover and casing being entirely outside the periphery of the impeller.

45

3. In a centrifugal pump, an impeller, a casing having an opening at its periphery large enough to permit the insertion of said 50 impeller, a cover for said opening, and a delivery branch in said cover, the line of the joint between said cover and casing being entirely outside of the periphery of the impeller.

55

4. In a centrifugal pump, an impeller, a casing having an opening at its periphery large enough to permit the insertion of said impeller, a cover for said opening, and a delivery branch, of gradually decreasing 60 section outwardly, in said cover, the line of the joint between said cover and casing being entirely outside of the periphery of the impeller.

60

In testimony whereof I affix my signature 65 in presence of two witnesses.

HENRI ARNOLD JOHANNES
de BIJLL NACHENIUS.
